ELECTRIC IRON

Application filed July 18, 1928. Serial No. 293,680.

This invention relates to improvements in electric flat irons and has for objects to provide a construction which has advantageous features with respect to current consumption, 5 mechanical efficiency and longevity.

This invention will be understood from the description in connection with the accompanying drawing in which Fig. 1 is an open side view, and Fig. 2 is a modification front 10 view.

In the drawing reference character 1 indicates an iron laminated core in contact with and electrically closed by the metal base 3. An insulated wire coil 2 is wound on core 1. 15 The core may be held in place by screws 4 and 5 which screw into the base 3 or other means of joining core to base 3 may be employed. Cover 6 may be fastened to base 3 by screws 7 and 8. Handle 9 is attached to cover 6 by screws 10 and 11. Terminals 12 and 13 are electrically connected through switch 14 to coil 2.

In the view shown in Fig. 2 the coil 2 is tapped and electrically connected to switch 14 by leads 15. Shoulders 20 and 21 are a further modification for securing core 2 to base 3.

Heretofore electric flat irons have employed high resistance alloy wire as a heating element. This heating element is placed upon the upper surface of the base of the iron and heat generated by the element is transmitted to the ironing surface by means of conduction. I have used the phenomenon 30 called hysteresis to generate heat within the base of the iron itself. My device is an electromagnetic iron having as its essential feature the rapid magnetization in alternate directions as a means of producing heat.

The alternating current passing through the coil 2 sets up a magnetic field and by placing any magnetic substance, notably the soft iron base 3 in the magnetic field, it becomes 5 temporarily a magnet with the poles and all other properties of a magnet. This effect on such a piece of iron is called "induction". The rapid magnetization in alternate directions due to the alternating current generated 0 heat in the base 3 of the iron.

A further advantage results from an extremely rapid vibration which is transmitted to the base of the iron and performs useful work in connection with ironing. The vibration amounts to actually striking the material being ironed a number of blows or impacts per second with the base of the iron 3. The vibrations may be made imperceptible or may be accentuated by closing and opening a space between the core 1 and the base 3 which may be regulated by means of screw 4.

Electric irons as manufactured at present in many instances provide heat regulating means. Fig. 2 shows a modification in which coil 2 is tapped at various stages of the winding each stage being connected to heat regulating switch 14 by leads 15. There is a relationship between the amount of heat generated in the base 3 and the number of turns of wire on core 1 thru which current is passed. Also, the diameter of wire is a factor. The tapped core 2 connected by leads 15 to switch 14 provides a means of regulating the temperature of the iron. Other temperature controlling means may be used.

I claim:

1. An electromagnetic iron, comprising a metal base and a metal core hinged thereon, said core providing means of generating vibrations within said base. 80
2. An electromagnetic iron, comprising a metal base and a metal core and insulated wire winding thereon, said core being placed in relation to said base in a manner to allow said core to vibrate in an upward and downward direction. 85
3. An electromagnetic iron, comprising a metal base and a metal core, and insulated wire winding thereon, said core being hinged to said base and providing means of striking impacts upon said base. 90
4. An electromagnetic iron, comprising a metal base and a metal core and an insulated wire winding, one end of said core being hingedly attached to said base, the other end of said core being free to vibrate in an arcuate direction. 95
